UNITED STATES PATENT OFFICE.

WILLIAM MURKLAND, OF LOWELL, MASSACHUSETTS.

LOOM.

Specification of Letters Patent No. 31,324, dated February 5, 1861.

To all whom it may concern:

Be it known that I, WILLIAM MURKLAND, of Lowell, in the county of Middlesex and State of Massachusetts, have invented a new 5 and useful Improvement in Looms, of which the following is a specification.

In many kinds of figured weaving, the filling threads are required to be of various colors, and this is especially the case in the 10 weaving of ingrain carpets.

Although the description of my invention is, in the following specification, limited to the carpet weaving yet the improvements are capable of being used upon similar fabrics requiring different colored filling threads. In ingrain carpet weaving, each figure to be produced upon the fabric often requires twenty or thirty different colors in the filling threads so that, in weaving 20 a yard or a yard and a half of carpet, twenty or thirty different shuttles, each carrying a different color, must be introduced.

My improvements are confined to the method of introducing these shuttles, without any regard to the other operations of the loom, which may be effected in any of the well known means.

Most looms in use for weaving plain fabrics and probably, most for weaving figured 30 fabrics, have their shuttles upon the lay of the loom, so that, as the lay swings forward to beat the filling into place by the reed, the shuttle moves forward with it and then returns back with it. This method is suitable for a few shuttles which can be moved 35 upon the lay so that each can be brought into the line of the race, to be thrown across the web; but when the number of shuttles is increased, they, together with their boxes 40 and appendages, become cumbersome, and by their weight, limit and control the speed of the loom; this is especially the case in carpet weaving, where the shuttles are necessarily large.

My improvements as I have arranged them, are adapted to that class of looms, which has its lay independent of the shuttle boxes and similar to that described by E. B. Bigelow in his patent of February 18th 1846, 50 in which the lay, at the extremity of its backward motion from the cloth, is at rest while the shuttle then required is thrown across. I shall particularly describe my improvements as applied to such a construction of loom, but they are equally applicable to others.

The prominent and controlling feature of my improvements, consists in providing a series of reserve shuttle boxes to contain the requisite number of shuttles that may be 60 desired, which reserve shuttle boxes are so arranged, that, so long as either of the shuttles contained in them is not required in the fabric, they will all remain, absolutely 65 without any movement or change of position, and when one of them is so required, it is then brought into connection with the active parts of the loom and worked so long as is necessary, and afterward put back into the quietude of the reserve series, and another taken from the reserve series, for use. 70 With this reserve series, I also provide for the working of another series of shuttle boxes, or a single shuttle box, to contain shuttles which are to be used in connection 75 with those of the reserve series. These I call the active series; the lower one alternates with those which are contained in the reserve series; and in order to bring one of the reserve series into use, the one last used 80 of the active series must be moved out of the working position of the shuttle, and vice versa, since there is but one race over which all the shuttles must be thrown.

The accompanying drawings represent an 85 arrangement of my improvements, wherein there are thirteen reserve shuttle boxes arranged in a cylindrical form about a center, and a series of two active shuttle boxes, above the reserve series, arranged to slide up 90 and down nearly vertically.

I have represented the contrivance as applied only to the right hand side of the loom, as that on the other side will be similar. Neither have I represented the cloth 95 making, and other parts of the loom, as they form no part of my invention.

Figure 1, is an elevation, looking from the rear or warp end of the loom, toward the cloth end. Fig. 2, is an elevation of the 100 side, looking in the direction in which the shuttles enter the warp. Fig. 3, is a skeleton drawing, showing the apparatus for shifting the reserve shuttle boxes in order to bring each of their shuttles into action. Fig. 4, is 105 a detached elevation of the protecting and carrying disk to prevent the reserve shuttles from moving forward when not in use. Fig. 5, is a detached view of one of the reserve shuttle boxes.

A, is a part of the frame of the body of 110 the loom.

B, is a side frame supporting the shuttle apparatus and has a stiffening bracket C.

The picking motion which propels the shuttles, is derived from the strap D, (not shown in the model) which is connected with the picking lever of the loom not here shown. This strap is attached to the arm E, which is fixed upon the end of the short shaft F, that has a suitable support in a hub 10 upon the side frame B. To the other end of the shaft F, the picker staff G, is fixed, extending downward and connected by the link H, to the picker I, (G, H and I not shown in model.) This picker is supported 15 and guided by the two picker rods J, J, in the ordinary manner, and the shuttle that for the time being, is in actual use, is presented before this picker in order to be thrown across the web.

20 As represented in the drawing the shuttle contained in the lower of the two active boxes is in position to be thrown. The active shuttle boxes K, K, are upon a frame L, L, which has V grooves upon its ends 25 fitted to slide upon corresponding V tongues upon the side frame B. These boxes have the ordinary friction binders M M, and springs N, N, to check and hold the shuttles. The frame L, L, is moved up and down, in 30 order to bring the required shuttle into position, by means of the rods O, O, (chains substituted for these rods in the model) chains P, P, wheels Q, Q, and rotating shaft R, R. This shaft is actuated by the cam Y, 35 operating upon the lever q, which is connected with the shaft R, R, by means of the rod r, pin z, and wheel l.

The reserve shuttle boxes S, S, S, S, S, S, 40 S, S, S, S, S, S, are arranged about a central shaft T, which is supported in bearings upon the side frame B. Attached to this shaft, near each end, are hubs having radial arms U, U, U, U, U, U, U, U, U, U, U, U, U, U, and the outer extremities of the radial arms 45 are connected by a polygonal circumference. Each of these radial arms has, projecting from it, a hub V, through which is formed a circular hole, having its axis in the direction of the radius, and also another hub 50 into which are inserted short pins W, W, W, &c. at right angles with the radiating arms, and parallel with the central shaft T. These pins are for the purpose of arresting and 55 retaining the polygonal reserve shuttle box frame in proper position, by their combination with the curved headed hammer X. This hammer has, extending downward from it, a spindle that is supported and guided in a stand upon the side frame B, 60 and by means of a spiral spring upon it, the curved head of the hammer is at all times pressed upward against the pins W, W, &c. and the most prominent part of the head of the hammer projects between the two ad-

jacent pins and prevents them from movement except by considerable force. Now when it is required to turn the polygon of reserve boxes, if sufficient force be applied, the hammer is forced downward and one of the pins traverses over the face or upper 70 surface, and the hammer will then rise between the next two pins and again hold the polygon with sufficient firmness. The force of the spring upon the spindle of the hammer and the form of its face are sufficient to 75 move the polygon slightly and insure that the two pins in contact with the hammer shall be brought to the same relative position with the hammer, and of course, insures a corresponding relative position of the 80 other parts attached to the polygon.

The shuttle boxes S, S, S, S, S, S, S, S, S, S, S, S, of the polygon, are made similar in their general parts to those of ordinary use, and are each provided with a binder 85 and spring to check and hold the shuttle. To the upper edge of the binder is a projection Z, seen in Fig. 5, which overlaps the shuttle and prevents its falling out of the box when at the lower portion of the polygon. At each end of the shuttle box is a groove to correspond and embrace the tongues that are on the side frame B, when this box is brought into use. From the bottom of each reserve shuttle box and near 90 each end of each, guiding spindles a, a, project and extend through the hubs V, V, &c. These guiding spindles allow the shuttle boxes to be moved away from the polygonal frame in the direction of the radius. Near 100 the ends of the guiding spindles, notches b, b, b, &c. are cut, which engages upon the semicircular, stationary, curved retaining piece c, so that, when the shuttle box is below the center of the polygon, it will not 105 fall out of the polygon frame, by its own weight.

The center of the polygonal frame is in a line with the centers of the two active shuttle boxes, and thus the uppermost of the 110 shuttle boxes of the reserve series is directly under and in the working line of the active shuttle boxes. Now when one of the reserve shuttles is required to be used, it must be brought up so as to come into line of the 115 movement of the picker I. To accomplish this, a lifting hook d, is attached to each end of the lower active shuttle box, and extends under the uppermost of the reserve shuttle boxes. Now when the active shuttle boxes 120 are raised, by rotating the shaft R, R, the reserve shuttle box is lifted up into the line of the picker, thus taking away the active shuttle box and replacing it by one of the reserve series, and the shuttle from the reserve shuttle box can be thrown across the web. It will be observed that this action 125 does not entirely separate the reserve shuttle

box from the polygonal frame, it being all the while guided and attached by the guide spindles *a*, *a*.

When the shuttle of the reserve box has completed its service, the shuttle box is lowered to its original place by the further rotation of the shaft *R*, *R*. In practice this movement up and down, alternating between the two shuttles, is ordinarily required to be regular so far as to bring the same change about, in from two to four beats of the lay, and is continued until the next shuttle of the reserve series is desired for service, when the whole polygonal frame, boxes and shuttles are made to rotate upon the centers, until the next shuttle is brought uppermost and in line with the active shuttles. This is accomplished by means of an apparatus shown in skeleton Fig. 3. This apparatus is situated at the opposite end of the polygonal frame, from the hammer and pins for retaining it in position heretofore described. The central shaft is shown at *T*, and thirteen pins *e*, *e*, *e*, *e*, *e*, *e*, *e*, &c., project from the polygonal frame in precisely the same manner as the pins *W*, *W*, *W*, &c., except that they are in the reverse direction, projecting toward the body of the loom, whereas the pins *W*, *W*, *W*, &c., project in the opposite direction.

By means of a cam *f*, and lever *g*, shown in Figs. 1 and 2, the connecting bar *h*, is caused to move down and up as often as there is a possibility of a change of the reserve shuttles required. This bar carries upon its upper end the sliding frame *p*, to which the hooks *i*, *i*, are jointed. These hooks are confined at a proper distance apart by the link *j*; to the middle of this link is jointed another link *k*, which at its other end is jointed to the *T* piece *s*. It will be seen, that so long as this *T* piece remains as shown in full lines, the sliding frame *p*, and its hooks, can be moved down and up again without the hooks engaging with the pins *e*, *e*, &c., but that, if the lower extremity of the *T* piece is moved to the left, the left hand hook will be brought into a position, so as to engage with one of the pins, so that when the hook is moved downward the pin will be moved by it. This position is shown in the drawing by dotted lines. It will also be seen, that if the lower part of the *T* piece had been moved to the right, instead of to the left, from its original position, that the right hand hook would have been in position to engage with the adjacent pin. It will also be seen that the downward movement of the frame *p*, and its hooks, will cause the polygonal frame to rotate a short distance in either direction, to the left or to the right, depending upon which of the two hooks is caused to engage with the pins.

The *T* piece *s*, has its vertical limb passing

through a slot in the supporting stand *L*, and its horizontal limb, being thicker, lies upon the upper surface of the stand. To each end of the horizontal limb is attached a string, and weights *m*, *m*, (for which, springs are substituted in the model) and to the same point are also attached knot cords, from the jacquard of the loom, which are not here shown. For the purpose of more conveniently illustrating the working of this apparatus a cam *t*, lever *u*, rod *v*, lever *w*, and hook *x*, shown in Fig. 1 have been substituted for the knot cords referred to.

In the practical working of the loom, either of the knot cords attached to the *T* piece, can be drawn up a short distance, at any stage of the weaving of the figure, in the same manner as each of the warp threads are drawn up. When the left hand side of the *T* piece is drawn up, by attaching the hook *x*, to it, the apparatus assumes the position shown in dotted lines, causing the left hand hook to engage with the pin, and the polygonal frame to turn to the left, and when the right hand side is drawn up, the whole apparatus takes the opposite direction.

It will be observed that the position of the polygonal reserve shuttle boxes and frame (as shown in the drawings) will not allow the descent of the upper of the two active sliding boxes, down to the line of the picker. In order to be able to do this, which is necessary to the full use of all the shuttles, an adjustment of the polygonal wheel is provided for, by sliding the polygonal frame down upon the side frame *B*, a distance equal to the depth of one of the shuttle boxes. This is an adjustment that is only required to be made, when a peculiar class of weaving is desired, and so long as the same figure or style of goods is being made, is not to be changed. This adjustment can be made by fastening the supporting bearings of the central shaft of the polygonal frame, at a point lower down upon the side frame *B*, shortening the bar *h*, and also lowering the *T* piece *s*.

In order to operate in making "plain two" "ply ingrain" carpet, the apparatus is arranged as shown in the drawings and the upper of the two active shuttle boxes is not used. In the weaving, if so many colors are required, all the shuttle boxes of the reserve series, on both sides of the loom, are filled with shuttles, and no shuttle is put into the shuttle boxes of the active series on either side of the loom. Now by bringing one of the shuttle boxes of the reserve series that is on the right hand side of the loom, opposite the race, and, on the other side of the loom the lower shuttle box of the active series opposite the race, a shuttle can then be thrown from the reserve shuttle box that

is on the right, to the active shuttle box that is on the left. The reserve box on the right is now lowered, bringing its connected active shuttle box in line of the race, and the 5 active shuttle box on the left and its connected reserve shuttle box, are raised, bringing the reserve shuttle box on the left hand side of the loom into the line of the race.

Now a shuttle can be thrown from the 10 reserve shuttle box on the left, to the active shuttle box on the right; a reverse movement of the shuttle boxes successively, will enable the shuttles to be thrown back again to their original boxes. If when they are 15 thus returned, it is desired to exchange them for others, then the polygonal shuttle box frame is turned upon its axis, as has been described, and another shuttle brought into use.

20 In order to weave "three ply ingrain carpet" or "shot and shot two ply ingrain carpet" the two boxes of the active series must be used on both sides of the loom. Also in order to weave "shot and shot three ply ingrain carpet" there must be three shuttle boxes in the active series on each side of the loom. Provision is shown in the drawing for lowering the polygon to meet this requirement, but only two active boxes are 25 shown; the third is to be placed above the two shown.

To provide for the contingency of a failure of the shuttle to fully enter its box when thrown across a protecting apparatus, similar to that used on this kind of loom, is provided, and its touching finger is shown at *n*, and as each shuttle box that is being used is brought to the same position, this one protector acts alike on all the shuttle boxes, and 35 in case of a failure of the shuttle to enter the box the loom is stopped by the action of this protector.

An annular ring marked *o*, shown fully 45 in Fig. 4, and drawn in blue lines on the other drawings, is supported upon small wheels at its inner edge, so as to have a free movement about its center. This ring is opposite the ends of the shuttles when in place, and prevents them from moving endwise out of their boxes. 50

In cases where the polygon of shuttles is continuously worked in one direction, the filling threads, leading from the shuttles to the cloth, can be cut and their ends attached to the ring, and, by revolving the ring the ends can be passed around the axis of the polygon, and any entanglement arising from the winding of the ends about the axis, may thus be avoided.

What I claim as my invention and desire to secure by Letters Patent, is—

1. The combination of the reserve shuttle boxes with the active shuttle boxes, by attaching and detaching the several reserve shuttle boxes, to and from the active shuttle boxes, under a construction and mode of operation, substantially as set forth.

2. The adjustment of the reserve shuttle boxes with the active shuttle boxes, so as to allow the use of one or more of the active 70 series, substantially as described.

3. The construction and use of the annular disk, for the purpose of keeping the shuttles in place, and for passing the ends of the yarns around the axis of the polygonal shuttle box frame.

4. The manner of holding the boxes of the polygonal frame in their position, by means of a segment of a circle or its equivalent.

WILLIAM MURKLAND.
